UNITED STATES PATENT OFFICE.

EVARISTO ABREGO, OF SAN ANTONIO, TEXAS.

MOTOR HEAD.

Application filed March 21, 1924. Serial No. 700,901.

To all whom it may concern:

Be it known that I, EVARISTO ABREGO, a citizen of the United States, residing at San Antonio, in the county of Bexar and State 5 of Texas, have invented a new and useful Motor Head, of which the following is a specification.

This invention relates to cylinder heads for combustion engines and the object there- 10 of is to so construct such a head as to provide means for continuously cleansing the spark plugs whereby the life of the plugs is lengthened and its effectiveness increased, all short circuits and ignition troubles at 15 this point being eliminated.

Another object is to provide a cylinder head with walls built around the intake valves and equipped with an opening located directly in front of the spark plugs so 20 that at every suction stroke of the engine the gas drawn into the explosion chamber will shift straight through the spark plug points whereby the points are washed at every operation thus producing a continu- 25 ous cleansing action on the plug.

With the foregoing and other objects in view which will appear as the description proceeds, the invention resides in the combination and arrangement of parts and in 30 the details of construction hereinafter described and claimed, it being understood that changes in the precise embodiment of the invention herein disclosed may be made within the scope of what is claimed without 35 departing from the spirit of the invention.

In the accompanying drawings

Figure 1 represents a bottom plan view of a portion of an engine cylinder head constructed in accordance with this invention.

Fig. 2 is a transverse section taken on the line 2-2 of Fig. 1, and

Fig. 3 is a longitudinal section taken on the line 3-3, Fig. 1.

In the embodiment illustrated, a cylinder head 1 is shown of the type used on Ford cars and which is equipped with the usual water jacket 2, the inner wall of which forms a dome-shaped ceiling 3 for the head,

This head 1 is equipped with the usual 50 chambers 4 and 5 which fit over the exhaust and intake valves 6 and 7 as is shown clearly in Fig. 1. The chamber 5 which houses the intake valve 7 is separated from chamber 4 by a wall 8 and from the chamber 55 10 which registers with the cylinder by a wall 9, the latter following the radius of the valve and cylinder but allowing for a clearance of both as is shown clearly in Fig. 1. An opening 11 is formed between 60 the walls 8 and 9 which opening is located directly in front of the spark plug 12.

It is of course well known that a clean spark plug makes the motor spark easy 65 when it is cold and this is insured by locating the points of the plug directly in the path of the gas sucked into the cylinder from the intake manifold through valve 7 and passage 11. When the motor is running the spark plug is protected by a cool 70 wash on every suction of the piston.

While this head is primarily intended for a Ford car motor, obviously the invention may be used in connection with any motor head that is, with any motor having 75 a detachable head. Any form of spark plug may be used in connection with this head.

What is claimed is:—

A cylinder head having a combustion 80 chamber therein, exhaust and intake valve housing chambers, a wall separating said chambers, a spark plug located adjacent the intake manifold chamber, said wall having an opening therein opposite the plug 85 for the passage of gas from the intake valve to the combustion chamber and in the path of which the ports of the point are located whereby each suction stroke of the engine cleanses the plug.

In testimony that I claim the foregoing as my own, I have hereto affixed my signature in the presence of two witnesses.

EVARISTO ABREGO.

Witnesses:

MAX R. SIMMAND,
D. J. MAN.
